DINNER PLATE OR SIMILAR ARTICLE

Monika Adams, West Hartford, Conn., assignor to Onondaga Pottery Company, Syracuse, N.Y., a corporation of New York

Filed Oct. 13, 1965, Ser. No. 87,451

Term of patent 14 years

(Cl. D44—15)

The figure is a fragmentary plan view of a dinner plate or similar article of conventional configuration showing my new design, it being understood that the ornamentation continues around the entire periphery of the pattern shown.

The drawing is shaded to indicate color contrast, but not to indicate any particular color.

I claim:

The ornamental design for a dinner plate or similar article, as shown and described.
